UNITED STATES PATENT OFFICE.

WILLIAM H. S. STRONG, OF SANDUSKY, OHIO.

MANGLE.

1,380,266.

Specification of Letters Patent. Patented May 31, 1921.

Application filed November 19, 1919. Serial No. 339,055.

To all whom it may concern:

Be it known that I, WILLIAM H. S. STRONG, residing at Sandusky, in the county of Erie and State of Ohio, have invented a certain 5 new and useful Improvement in Mangles, of which the following is a full, clear, and exact description, reference being had to the accompanying drawings.

This invention relates primarily to improved controlling means for mangles.

In the operation of ironing clothes by the use of a mangle, it is necessary at times to vary the space between the feed roller and the heated iron, to accommodate work of 15 different thicknesses, widening this space, of course, facilitating insertion and permitting the withdrawal of the work without necessitating its being passed completely through the machine. It is desirable, however, 20 that the force, such as spring tension, holding the iron against the work, should remain active throughout the variations of the feeding space, and that both hands of the operator be left available for handling 25 the work. It is also occasionally desirable to stop the rotation of the feed roll while the iron is held momentarily away from the feed roll, and at other times to permit this separation to take place while the feed roll 30 continues to revolve.

An object of my invention is to provide means whereby the results above mentioned may be conveniently and practically attained. Another object is the arrangement 35 of foot controlled means for separating the feed roll and heating iron, with provision of additional apparatus, which may be set, when desired, either to cause the foot controlled separating movement to disconnect 40 the roll from its driving means, or to permit the drive to remain uninterrupted. A further object is the provision of an efficient safety device whereby if an operator's fingers or sleeve should be caught between the 45 roll and iron these two members will become separated and prevent serious injury to the operator.

These and other objects will become apparent as the description proceeds. A preferred embodiment of my invention is illustrated in the accompanying drawings and the essential characteristics are summarized in the claims.

In the drawings, Figure 1 is a vertical section through my improved mangle showing parts in end elevation; Fig. 2 is a plan of

the same; Fig. 3 is a front elevation, parts being in section; Fig. 4 is an end elevation of the driving mechanism, the housing therefor being removed; and Fig. 5 is a detail showing parts in different position from that illustrated in Fig. 1.

Referring to the drawings by numerals, 10 designates the work table of a power driven mangle, supported by a frame 11 resting on a bench or support 12. The usual 65 felt covered feed roll is shown at 15 fixed on a shaft 16, mounted in bearings 17 on the frame 11, while the numeral 18 designates a heating iron mounted adjacent to the 70 roll 15. A pipe leading to burners (not shown) for heating the iron 18, is shown at 80 in Figs. 1 and 5. The shaft 16 is shown extending through one end of the frame 11 into a housing 20 secured thereto, 75 in which its end has a bearing as at 21. Carried loosely on the shaft 16 and releasably connected therewith by a clutch mechanism hereinafter described, is a worm gear 23 in driven engagement with a worm 25, 80 on a drive shaft 22, mounted in a sleeve 24, rigidly secured to the frame 11 as by a bracket 26. The shaft 22 extends rearwardly 85 of the machine and is driven by any suitable power mechanism (not shown).

The iron 18 is preferably held against the roll 15 under the tension of springs 30 having their upper ends connected as at 31 to the iron and their lower ends embracing 90 blocks 32 constituting rock arms mounted on a rock shaft 33. Adjusting screws 35 may be provided to pass through lugs 34 secured to the iron 18 to vary the tension of the springs 30.

A rock shaft 40 is mounted below the iron 95 18 in bearings 41 in the frame 11, and has cams 43 secured thereto adjacent to each of the springs 30, adapted to engage the springs. To rock the shaft 40 an arm is secured as at 45, having a link 46 pivoted thereto and 100 to a foot board or pedal 48. Depression of the pedal by the foot of the operator will rotate the shaft 40 and cause the cams 43 to bear against the springs 30 and force them and the iron 18 away from the feed roll 15 105 to an extent depending upon the pressure exerted on the pedal.

The shaft 40 projects through the bearing 41 into the housing 20 and has secured thereto a rock arm 50 constituting part of a 110 clutch release mechanism whereby the shaft 16 and worm gear 23 may be disconnected.

This clutch mechanism comprises a peripherally grooved collar 55 splined as at 58 to the shaft 16. The collar has a tongue and slot connection 56 with the gear 23, which 5 is normally closed under the influence of a spring 68 surrounding the shaft. Loosely embracing the peripheral groove is a yoke 59, which is in turn embraced by and pivotally connected to the upper bifurcated arm 10 60 of a bell crank pivoted at 62 to the lower end of a hand lever 65.

The other arm 66 of the bell crank extends parallel with the rock shaft 40, and when the hand lever 65 is in the position 15 shown in full lines in Fig. 4 is adapted to be engaged by the rock arm 50. Depression of the pedal 48 actuates therefore the cams 43, and also tilts the arm 50 upwardly, thereby swinging the bell crank arm 66 upwardly 20 and the bifurcated arm 60 inwardly toward the roll 15, thereby causing the collar 55 to be moved along the shaft 16 against the tension of the spring 68, thereby breaking the clutch connection at 56 with the gear 23.

25 If it is desired to separate the iron 18 and roll 15 by actuation of the cams 43 from the foot pedal 48 without stopping the roll 15 by breaking its clutch connection with the shaft 16 and gear 23 at 56, the hand lever 65 may 30 be swung rearwardly about its pivot on the shaft 16, thereby oscillating the bell crank 60 embracing the yoke 59 within the groove of the collar 55, and disengaging the arm 66 of the bell crank from the rock arm 50, as 35 shown in dotted lines in Fig. 4. The bell crank being thus moved manually when desired, out of the path of the rock arm 50 by movement of the hand lever 65, oscillation of the rock shaft 40 will cause idle upward 40 movement of the arm 50.

Safety mechanism is provided comprising a bar 70 positioned above the roll 15 and the heater 18 and connected by curved arms 72 with a rock shaft 73 having rock arms 74 45 adjustably connected to the spring blocks or rock arms 32. This connection comprises a turnbuckle having right and left hand threaded links 76 connected by a nut 77, and the parts are so arranged that rearward 50 movement of the bar 70 will rock the shafts 73 and 33 and move the iron 18 away from the roll 15 through rearward movement of the springs 30. If the fingers or sleeve of the operator should become caught between the 55 roll and iron his arm will immediately strike the bar 70 and effect the disengagement of the parts as indicated, and thereby avert possible serious injury.

In operation, the hand lever 65 will be set 60 in either of its two positions according as it is desired or not to disconnect the drive to the roll when the pedal 48 is depressed. With the lever 65 pushed rearwardly as shown in Figs. 1 and 4, the bell crank arm 66 65 will be out of the path of the rock arm 50,

so that oscillation of the rock shaft 40 will merely cam the iron 18 away from the roll 15 as shown in Fig. 5, leaving the drive to the roll uninterrupted. When the lever 65 is in forward position, however, as shown in 70 full lines in Fig. 4, the bell crank arm 66 is in the path of the rock arm 50, and upward movement of the latter, occasioned by downward movement of the pedal 48, will shift the collar 55 longitudinally on the shaft 16 75 and disconnect the worm gear 23 from the shaft 16. Thus, the movement of the roll 15 will be stopped so long as the pedal is depressed, and, as in the preceding instance, the cams 43 will be actuated to separate the 80 iron from the roll an amount depending upon the amount of movement given to the pedal 48.

In the above manner the iron may be 85 moved away from the roll to facilitate insertion or removal of the pieces to be ironed without releasing the spring tension tending to hold them together, and without necessitating for this purpose the use of either hand or its removal even temporarily from 90 the work. By a simple setting of a lever this same operation will simultaneously either disconnect the drive to the roll or permit it to continue uninterrupted as desired.

I claim—

1. In a mangle the combination with a rotating feed roll, a driving connection therefor, an iron pressed against the roll, manually operable means for separating the iron from the roll, foot operable means connected 100 with the iron and driving connection, whereby a movement of the foot operable means may separate the iron from the roll and disengage the driving connection, and other manually operable means associated with the 105 driving connection and adapted to coöperate with the foot controlled means, whereby the foot controlled means may be operated to move the iron away from the roll without disengaging the driving connection.

2. In a mangle, a work-supporting table, a feed roll, a heating iron adjacent to said roll, a rock shaft, leaf springs pivotally mounted on said rock shaft and adapted to force said iron toward said roll, cams adapted to engage said springs, and means for actuating said cams to cause varying degrees of separation of said iron and roll.

3. In a mangle, the combination with a driven roll, and an iron connecting means 120 between said roll and the driving gear, foot controlled means for interrupting the drive to said roll, and hand controlled means acting on said connecting means for rendering said foot controlled means operative or inoperative.

4. In a device of the character described, the combination with a power driven feed roll, of a heating iron pressed against the roll, a clutch for effecting the interruption

of the drive to said roll, foot controlled means for varying the pressure of the iron against the roll, and a manually movable member connecting the foot controlled means with the clutch.

5. In a mangle, the combination with a heating iron, of a feed roll having a member separably connecting it with driving means therefor, means comprising a foot controlled 10 rock shaft, whereby said roll and iron may be separated at will, connecting means between the rock shaft and said member and a manually controlled lever for causing engagement or disengagement of said connecting means with said rock shaft.

6. In a mangle, a rotating feed roll, driving gear therefor, a heating iron adjacent said roll, a clutch connection between said roll and its driving gear, a bell crank in engagement with the clutch, a lever associated with said bell crank, a rock arm for engaging the bell crank to shift the lever for swinging it out of the path of the rock arm.

7. In a mangle having a rotating feed roll 25 and an iron spring pressed thereagainst, a normally closed clutch connection between said roll and its driving gear, means controlled by the foot of the operator for varying the distance between said iron and roll, 30 and manually shiftable means whereby in one position said clutch connection may be opened by actuating said foot controlled means.

8. The combination with the feed roll of 35 a mangle and the heating iron therefor, a shaft for said roll, a gear removably connected to said shaft, by clutch mechanism having two positions, manually controlled means for shifting said mechanism into 40 either of its positions, and foot controlled means for engaging said iron and variably spacing it from said roll, and having a part adapted to simultaneously intersect one of said clutch mechanism positions.

45 9. The combination with the feed roll of a mangle and the heating iron therefor, a shaft for said roll having a clutch connection with a driving gear, manually controlled means in engagement with said 50 clutch, and foot controlled means for variably spacing said roll and iron and simultaneously controlling said clutch to disconnect the drive or leave the same undisturbed depending upon the setting of said manual 55 means.

10. In a mangle, a feed roll and iron, said feed roll having a shaft, a driving gear on said shaft, a member separably connecting said shaft and gear, means for actuating said 60 member comprising a lever having one arm pivotally connected with said member, a rock shaft having an arm adapted to extend into the path of said lever, and means for oscillating said rock shaft.

65 11. In a device of the character described,

a feed roll and a heating iron adjacent thereto, a rotatable shaft carrying a clutch connection between said shaft and a driving gear, a rock shaft having means thereon adapted to shift said iron from said roll, 70 means for connecting or disconnecting said clutch with said rock shaft and controllable means for oscillating said rock shaft, whereby said iron and roll may be separated a desired amount, and the drive to said feed roll 75 interrupted or not, as desired.

12. In a mangle, a frame and feed roll, an iron supported in said frame, said feed roll having a shaft projecting from one side of said frame, a rock shaft extending through 80 said frame, means for oscillating the rock shaft, a driving gear loosely mounted on the feed roll shaft, a collar splined on said shaft and spring pressed toward said gear, a tongue and groove connection between 85 said roller and gear, a bell crank having one arm pivotally connected with said collar, and means for swinging said bell crank about said pivot into or out of engagement with said rock shaft.

90 13. In a device of the character described, the combination of a work supporting platform, a feed roll adjacent thereto, a movable heating iron, springs tending to hold it tightly against said roll, means on said iron 95 for adjusting the tension of said springs, a rock shaft, cams carried by said shaft adapted to engage said springs, and means for oscillating said rock shaft, whereby said cams may separate the iron from the roll. 100

14. In a device of the character described, the combination of a work supporting platform, a feed roll adjacent thereto, a heating iron supported from a rock shaft by springs tending to hold it tightly against said roll, 105 means on said iron for adjusting the tension of said springs, a second rock shaft, cams carried by said last named shaft adapted to engage said springs, and means for oscillating said second rock shaft, whereby said 110 cams will engage said springs and separate the iron from the roll.

15. In a mangle having a work table and feed roll, a heating iron supported adjacent thereto, springs tending to press said iron 115 against said roll, a rod extending parallel to and above said roll and iron adapted to be engaged by the arm of the operator in case his fingers become caught between the roll and iron, rock arms connected with said 120 rod, and mechanism connecting the rock arms with said springs, whereby movement of the rod will separate said iron and roll.

16. A mangle having a work table, a feed roll and a heating iron in approximately the 125 same horizontal plane, springs tending to press said iron against said roll, a bar above said roll adjustably connected with said springs, and adapted to be engaged by the arm of the operator in case his fingers be- 130

4
come caught between the iron and the roll, whereby said iron and said roll will be instantly separated.

17. In a mangle the combination with a 5 rotating feed roll, of an iron, means for forcing them toward each other, means for varying the distance between said iron and roll by foot power, a driving member, a clutch between the said roll and the driving

member and manually operable means associated with the clutch, whereby the foot power means may be operated to move the iron either with or without disengaging the said roll from the driving member. 10

In testimony whereof I hereunto affix my 15 signature.

WILLIAM H. S. STRONG.
